UNITED STATES PATENT OFFICE.

ARTHUR MEYER, OF GENEVA, SWITZERLAND.

CARTRIDGE-BELT.

SPECIFICATION forming part of Letters Patent No. 691,403, dated January 21, 1902.

Application filed June 21, 1901. Serial No. 65,534. (No model.)

To all whom it may concern:

Be it known that I, ARTHUR MEYER, a citizen of the Republic of Switzerland, and a resident of Geneva, Switzerland, have invented 5 certain new and useful Improvements in Cartridge-Belts, of which the following is a specification.

My invention relates to cartridge-belts, the object being to provide an improved device 10 of this kind adapted to fit perfectly around the waist without being tightened thereon.

A further object is to provide a cartridge-belt made of two parts, which may be employed independently when desired.

15 In the accompanying drawings, Figure 1 is a front elevation of a portion of a coat with the cartridge-belt applied thereto. Fig. 2 is a corresponding rear elevation. Fig. 3 is an enlarged front elevation showing a fastening 20 hook and loop. Fig. 4 is a corresponding side elevation. Fig. 5 is an enlarged view of a fastening-button.

The improved cartridge-belt comprises two halves *a* and *b*, each provided with a series of 25 holders or pockets and provided at one end with a buckle *c* and at the other end with a strap *i*, provided with a series of holes for the reception of the tongue of the buckle. Each belt comprises also two safety-pins *e*, having 30 hooks *f*, and a safety-pin *g*, provided with a button *h*. The two halves of the belt are connected to each other by means of the straps *i* and buckles *c*. The pin *g* is fastened at the desired height to the back of the coat, Fig. 35 2, while the pins *e* are attached at the same height to the sides of the coat, whereupon the belt is closed by connecting the strap *i* with the adjacent buckle, and it is hooked to the coat by fitting the eyes *k* of the buckles *c* 40 over the hooks *f* of the pins *e* and by inserting the button *h* into the rear buttonhole *d*, the front buttonhole *d* receiving one of the

buttons of the coat. When the front half of the belt is emptied, and when it is desired to bring the rear half to the front, all that is required is to disengage the loops *d* from the retaining-buttons and the buckles *c* from the hooks *f*, whereupon the belt may be easily moved around the waist and again attached to the coat, as before described.

Each buckle *c* is provided with a safety-pin *l*, Fig. 4, made integral therewith and enabling said buckles to be directly attached to the coat without the agency of the hook-pins *e*. This feature of my invention is very useful 55 when one of the pins *e* has been lost.

The pin *l* of the buckle *c* is pivotally connected to the latter at *k* in a manner similar to that in which a lady's brooch-pin is fixed to the brooch. This is a great advantage, for 60 when the pin is broken or bent it is easily replaced.

Having fully described my invention, what I claim, and desire to secure by Letters Patent, is—

The improved cartridge-belt, comprising two detachable halves, buckles for connecting the free ends of said halves, eyes provided on said buckles, safety-pins adapted to be attached to the garment and provided with 70 hooks for the reception of said eyes, a suitable buttonhole between the ends of each belt-half, safety-pins adapted to be attached to the garment and provided with buttons for the reception of said buttonholes and a safety-pin pivotally connected to each buckle, substantially as and for the purpose set forth.

In testimony whereof I have hereunto set my hand in presence of two witnesses.

ARTHUR MEYER.
